UNITED STATES PATENT OFFICE.

WILLIAM G. REYNOLDS, OF CHICAGO, ILLINOIS.

PRINTING APPARATUS.

SPECIFICATION forming part of Letters Patent No. 714,744, dated December 2, 1902.

Application filed January 27, 1902. Serial No. 91,505. (No model.)

To all whom it may concern:

Be it known that I, WILLIAM G. REYNOLDS, a citizen of the United States, residing at Chicago, in the county of Cook and State of Illinois, have invented certain new and useful Improvements in Printing Apparatus, of which the following is a specification.

The object of this invention is the production of an apparatus for printing; and it refers particularly to printing-plates each containing one or more letters or words, to a means for supporting and a means for holding said printing-plates in position, to a means for permitting the breaking away of a portion of a printing-plate and the insertion of another smaller plate to make changes in the matter appearing upon the larger plate, and to the details of construction herein shown and described.

In the accompanying drawings, Figure 1 is a face view of a galley adapted to receive the printing-plates of my invention. Fig. 2 is a transverse sectional view on dotted line 2 2 of Fig. 1. Fig. 3 is a perspective view of a four-line printing-plate. Fig. 4 is a perspective view of the same plate after a portion of said plate has been broken away and a smaller plate substituted in order to make a change in the date appearing upon the plate in Fig. 3. Fig. 5 is a perspective view of one of said smaller plates. Fig. 6 is a perspective view of a plate provided with only one securing-flange. Fig. 7 illustrates a plate adapted to be used in a galley wherein the bars extend transversely instead of longitudinally. Fig. 8 is a perspective view illustrating a modification in the form of the galley-bars and a corresponding change in the flanges of the printing-plates.

My invention is here represented in its application to a mailing-list.

Printing-plates embodying my invention are formed, preferably, of sheet metal with a single letter, a word, or several words embossed upon the face thereof. The ends of the plate are turned down, preferably at right angles to the face of the plate, and if there are several lines upon the plate it is gained, grooved, or indented between the lines in order to provide for the easy separation by breaking apart of the different lines. The

flange at each end of the plate is cut at points coinciding with the indentations between the lines.

A represents a printing-plate of my invention, A' is the face or body portion thereof, and A² represents the flanges at the ends of said plate. A³ represents the slits cut in the flanges, and A⁴ represents the gains or indentations separating the lines of the plate. The plates shown in the drawings are for the mailing-list of a newspaper, each plate showing the name and address of the subscriber and the date upon which his subscription expires. This date is usually placed upon the plate so that the number representing the year shall appear in one corner of the plate, and a portion of said plate containing one or more of the numerals making up the year is adapted to be broken away from the remainder of the plate by means of the indentation A⁶, extending at right angles to a prolongation A⁷ of the slit A³. When it is desired to change the date to which a subscription is paid, that portion of the plate which contains the numeral or numerals to be changed is broken away and replaced by a smaller plate corresponding in size to the portion removed and bearing the numeral or numerals necessary to make up the new date. The galley adapted to receive these printing-plates comprises bars B, separated by and having at their sides strips B'. The bars and strips are held in position side by side by bolts B², passing through suitable openings in the bars and the strips, said bolts being provided at their ends with wing-nuts B³ to clamp the bars tightly together. In practice the bars B are made of wood and the strips B' of thin metal. When it is desirable to secure the printing-plates A within the galley, the wing-nuts B³ are loosened and the plates placed in columns upon the several bars of the galley, with the flanges A² between the strips B' and the bars B. When all the plates are in position, the wing-nuts are tightened and the galley is ready for the press. The strips B' between the bars B of the galley permit the sliding of the plates upon any particular bar without interfering with those upon the bar next adjacent. The plates are gained or grooved to permit of the breaking off of any particular

line in order to change the address of any subscriber or to change the date to which a subscription is paid.

It is clear that the width of a column might 5 be represented by the length of the bars B, the bolts B² extending lengthwise of the column, in which event printing-plates similar to that shown in Fig. 7 would be employed and each plate would bear only one letter. 10 Such a plate might have two flanges A² or only one.

In the modification shown in Fig. 8 the flanges of the printing-plates C grasp a dovetail C', formed upon the upper face of the galley-bars C². In other respects the form shown 15 in said figure is the same as the invention shown in the other views of the drawings.

It is apparent that various changes might be resorted to in the general form and arrangement of the several parts herein described without departing from the spirit and scope of my invention, wherefore I wish to have it understood that I do not desire to limit myself to the precise details set forth. 20

25 I claim as my invention—

1. As a new article of manufacture, a printing-plate having a groove or indentation in its body portion, and a flange at one edge of said plate, said flange having a slit coinciding with one end of said groove or indentation. 30

2. As a new article of manufacture, a printing-plate having two grooves or indentations in its body portion, one extending substantially at right angles to the other, and a flange 35 at one edge of said plate, said flange having a slit coinciding with one of said grooves or indentations.

3. As a new article of manufacture, a composite printing-plate bearing upon its face a 40 letter, character or word, said plate having a securing-flange at each of its two opposite edges, a portion of said plate and of one of its flanges being removed; in combination with a supplemental plate bearing upon its face a letter, character or word and adapted to complete the main plate, said supplemental plate having a securing-flange at one of its edges. 45

4. In a printing apparatus, a printing-plate 50 bearing upon its face a letter, character or word, said plate having a securing-flange extending substantially at right angles from its face at two of its opposite edges; in combination with a galley-frame comprising bars 55 adapted to receive said flanges between them, separating - strips between the bars, and

means for clamping said bars and said strips together.

5. In a printing apparatus, a printing-plate bearing upon its face a letter, character or word, said plate having a securing-flange extending substantially at right angles to its face at two of its opposite edges, a groove or indentation in its body portion and a slit coinciding with one end of said groove or indentation; in combination with a galley-frame comprising bars adapted to receive said flanges between them; separating-strips between said bars; and means for clamping said strips and said bars together. 70

6. In a printing apparatus, a printing-plate bearing upon its face a letter, character or word, said plate having a securing-flange extending substantially at right angles to its face at two of its opposite edges, two grooves 75 or indentations in its body portion, one extending substantially at right angles to the other, and a slit in one of said flanges coinciding with one of said grooves or indentations; in combination with a galley-frame comprising bars adapted to receive said flanges between them; separating-strips between the bars; and means for clamping said bars and said strips together. 80

7. In a printing apparatus, a printing-plate bearing upon its face a letter, character or word, said plate having a securing-flange, also having an indentation; and a supplementary plate having a face adapted to lie within said indentation, and a flange; in 90 combination with a galley-frame comprising bars adapted to receive the flanges of said plates between them, and means for clamping said bars together.

8. In a printing apparatus, a printing-plate 95 bearing upon its face a letter, character or word, said plate also having a securing-flange extending substantially at right angles to its face at two of its opposite edges; in combination with a galley-frame comprising bars 100 adapted to receive said flanges between them, said bars having coinciding openings extending transversely through them; separating-strips between the bars; and bolts extending through the openings in the bars and being 105 provided with nuts to clamp said bars and said strips together.

WILLIAM G. REYNOLDS.
